COMPRESSOR AND THE LIKE

Rasmus M. Hvid, Wilmette, Ill.

Application March 14, 1941, Serial No. 383,245

14 Claims. (Cl. 230—173)

This invention relates to compressors, pumps, pressure motors and the like, more particularly to motor-compressor units for use in hermetically sealed casings or housings, and the invention has for an object the provision of compact and efficient compressor or pump units of this character.

It is becoming more and more the accepted practice in the construction of refrigerating apparatus, particularly household refrigerators of the type utilizing a closed compressor-condenser-expander cycle, to house the compressor and its driving motor within a permanently and hermetically sealed casing. Such arrangements of course require a compact construction of the motor and compressor unit which will be trouble-free and capable of operation over long periods of time without servicing or repairs. While various compressor units have heretofore been proposed and adopted for use in such refrigerating systems, problems have been encountered due to failure of the compressor parts or to faulty operation of the compressor valves, and something is yet to be desired in motor-compressor units of this character.

It is a further object of this invention to provide a compact and efficient valveless compressor, pump or motor of the reciprocating type having intake and discharge ports controlled solely by movements imparted to the reciprocating piston, and wherein the necessity for separately operated valves is entirely eliminated.

In carrying out my invention in one form I provide a compressor having a cylinder extending in the same axial direction but offset from the rotating drive shaft, a piston mounted in the cylinder for both rotary and reciprocatory movement therein, and a driving connection between the rotating shaft and the piston for moving the piston through one complete rotation during each complete reciprocation thereof. Suitable valve ports are provided in the cylinder wall and in one face of the piston, which valve ports are so disposed in cooperative relation that the rotary movement of the piston effects properly timed suction and compression strokes as the piston reciprocates.

For a more complete understanding of my invention, reference should now be had to the drawings, in which:

Fig. 1 is a vertical sectional view taken substantially along the line 1—1 of Fig. 2;

Fig. 2 is a horizontal sectional view taken along the line 2—2 of Fig. 1;

Fig. 3 is a horizontal sectional view taken substantially along the line 3—3 of Fig. 1;

Figs. 4 and 5 are fragmentary vertical sectional views taken along the lines 4—4 and 5—5, respectively, of Fig. 3;

Figs. 6 and 7 are similar vertical sectional views taken along the lines 6—6 and 7—7, respectively, of Fig. 2;

Fig. 8 is a detail sectional view taken substantially along the center line of the wrist pin for the reciprocating and rotating piston shown in Fig. 1; and

Fig. 9 is a somewhat diagrammatic elevational sectional view showing a modification of the invention as applied to an internal combustion engine.

Referring now to Figs. 1 to 8, inclusive, of the drawings, the invention is shown as embodied in a hermetically sealed motor-compressor unit 20 wherein the hermetically sealed casing, which is formed of an upper shell 10 and a lower shell 11, forms the low pressure side of the refrigerating apparatus. The motor, which may be of standard construction, comprises a stator winding 12 mounted upon a laminated stator frame 13 within which is disposed the rotor 14, the rotor being mounted on a suitable shaft 15 having an enlarged cylindrical head 16 on its lower end. As shown, the stator frame 13 is mounted, with a pressed fit, within the open upper end of a cup-shaped supporting member or shell 17, the lower wall of which is formed to provide a re-entrant portion 18 having a centrally located aperture therein through which the shaft 15 of the motor extends.

Disposed within the re-entrant portion 18 of the supporting shell 17 is a bearing ring 19 within which the cylindrical head 16 on the motor shaft is located and provided with a running fit, and a suitably shaped casting 21 is provided which is supported below the bearing ring 19 and secured thereto and to the supporting shell 17 by a plurality of bolts 22, as shown best in Figs. 3 and 6. The upper surface of the casting 21 and the lower surface of the re-entrant portion 18 on the supporting shell 17 engage the lower and upper surfaces, respectively, of the enlarged head 16 on the motor shaft 15, a close running fit being provided between these respective surfaces. Secured to the bottom of the casting 21 by suitable bolts, as shown in Fig. 1, is a closure plate 22a.

As shown best in Figs. 1 and 2, the casting 21 is shaped to provide a vertically extending cylinder 23 having an intake port 24 which com-

municates with an intake chamber 25, and an outlet port 28 which communicates with an outlet chamber 21. Disposed within the cylinder 23 is a piston 28, one wall of which is provided adjacent the lower end of the piston with a port 28 arranged to cooperate with the intake and outlet ports 24 and 26, respectively, in a manner which will be more fully described hereinafter. The piston 28 is hollow, as shown best in Fig. 1, and is provided intermediate its ends with a suitable wrist pin 30 to which is pivotally connected a connecting rod 31, the opposite end of the connecting rod being pivotally connected, preferably by means of a ball and socket joint, to the enlarged head 16 on the motor shaft 15. The ball 32, which is formed on the outer end of the connecting rod 31, is located within a socket 33 formed in one face of the head 16 and retained therein by a suitable disc 34 which is provided with a spherical face 35 and is slotted at 36, as shown best in Fig. 3, to permit the desired movement of the connecting rod 31, the socket 33 and the face 35 on the disc 34 forming a substantially spherical seat for the ball 32.

The socket 33, in which the ball 32 on the upper end of the connecting rod 31 is located, is offset from the axial center of the shaft 15 and the enlarged head 16 a distance considerably greater than the offset distance between the center line of the shaft and the center line of the cylinder 23. This relation between the socket 33, the center line of the shaft 15 and the center line of the cylinder 23 is highly desirable in order to insure that the socket 33 never occupies a position coincident with the center line of the piston 28, in which position rotation of the piston would be possible independently of any movement of the head 16.

When the parts are in the position shown in Fig. 1, the piston 28 is at the upper end of its stroke, and when the head 16 has rotated through 180° the socket 33 will have approached the center line of the piston 28 so that the piston will occupy its lowermost position in the cylinder 23. During the next 180° of movement of the head 16 the piston will be returned to the upper end of its stroke. Each rotation of the head 16 causes the piston 28 to rotate in the cylinder 23 and this rotative movement is utilized to control the intake and discharge of the gas to be compressed within the cylinder 23. If the offset distance of the socket 33 from the center line of the shaft 15 were only slightly greater than the offset distance between the center line of the cylinder 23 and the shaft 15, respectively, a considerably larger turning force would be required to rotate the piston when the ball and socket approach a position closely adjacent the center line of the piston and cylinder. Accordingly a substantial difference in these offset distances is preferred, as shown.

The hermetically sealed casing formed by the shells 10 and 11, within which the motor-compressor unit is located, is connected to the low pressure side of the refrigerating system by means of a suitable inlet pipe 37 which extends through a wall of the shell 10 adjacent the upper end of the casing, and the lower portion of the casing contains a body of lubricating fluid which extends approximately to the level indicated by the line 38. During operation of the motor-compressor unit this body of lubricating fluid will be subjected to considerable disturbance, and in order to insure that the lubricant is not drawn into the intake chamber 25 of the

compressor, this chamber is connected to the interior of the hermetically sealed casing by means of a port 39 which, as shown in Fig. 5, extends through the casting 21, the bearing ring 19, and the portion 18 of the shell 11, so that the communication occurs just below the motor and at a considerable distance above the body of oil. Also extending through a wall of the shell 10 is a discharge conduit or pipe 40 which is connected to the high side of the refrigerating system and to the discharge chamber 21 of the compressor, as shown best in Figs. 2 and 7, a suitable fitting 41 (Fig. 7) providing a pressure-tight connection between the conduit 40 and the discharge chamber 21.

In order to insure that the piston and cylinder are properly lubricated, a small oil pump is provided for transferring lubricating fluid from the body of oil contained in the hermetically sealed chamber to the walls of the cylinder 23 under suitable pressure. This oil pump is formed, as shown best in Figs. 1 and 3, by cutting back a narrow band on the upper portion of the enlarged head 16 to provide an eccentric surface 42. Engaging this eccentric surface is a spring-pressed follower 43 which is located in the bearing ring 19, an intake duct 44 being disposed on one side of the spring-pressed follower 43 and a discharge duct 45 (Fig. 3) being disposed on the opposite side of the follower 43.

As shown in Fig. 1, the intake duct 44 extends downwardly through the casting 21 to a point below the level of the body of lubricating fluid within the casing, and, as shown in Fig. 4, the discharge duct 45 communicates with an oil groove 46 which extends about the wall of the cylinder 23. When the shaft 15 and the head 16 rotate in the direction indicated by the arrow in Fig. 3, the oil pump provided by the eccentric portion 42 and the follower 43 will cause oil to be drawn up through the duct 44 and expelled under pressure through the discharge duct 45, and it will be apparent that, by providing oil grooves in the various faces of the head 16, the running surfaces between the head, the bearing ring 19 and the members 18 and 21 may be effectively lubricated.

With the above description of the various elements in mind, it is believed that a complete understanding of this invention may be had from a description of the operation. As heretofore indicated, when the shaft 15 of the motor is rotated, the head 16 on the lower end of the shaft drives the piston 28 through the connecting rod 31 so as to effect one complete rotation and one complete reciprocation of the piston 28 during each revolution of the shaft 15. During this rotation the ball 32 on the upper end of the connecting rod 31 pivots in its socket 33, and during this pivotal movement moves toward and away from the center line of the cylinder 23 so as to reciprocate the piston.

As shown best in Fig. 2, the intake port 24, which establishes communication between the intake chamber 25 and the lower portion of the cylinder 23 when the port 29 in the piston is opposite the port 24, extends about a substantial portion of the circumference of the cylinder, i. e., between the shoulders 52 and 48 (Fig. 2). The piston 28 occupies its upper dead center position when the port 29 in the piston is substantially opposite the shoulder 51 and accordingly the port 29 is in communication with the intake port 24 during substantially the entire

suction stroke. Shortly after the piston 28 has passed its upper dead center position, however, the port 29 in the wall of the piston moves past the shoulder 48, whereupon communication between the cylinder 23 and the intake chamber 25 is cut off and pressure begins to build up within the cylinder 23. The feature of maintaining the inlet port 24 open for a short time after the piston 28 has passed the dead center position affords better charging of the cylinder than would otherwise be obtained. When the intake port 29 passes the shoulder 49 (Fig. 2) in the cylinder wall, the cylinder 23 is placed in communication with the discharge passageway 26.

Pressure continues to build up as the piston 28 is rotated and reciprocated, and the compressed gas is thus discharged from the cylinder 23 through the discharge port 26 and into the discharge chamber 27. Disposed between the discharge port 26 and the discharge chamber 27 is a normally closed spring-pressed check valve 50 which opens as soon as the pressure in the cylinder 23 exceeds the pressure at which the check valve will open. It will of course be understood that the back pressure in the chamber 27 and the pressure exerted by the check valve spring cooperate to determine the total pressure at which the check valve 50 will open. The purpose of this check valve is primarily to prevent circulation between the high and low sides of the compressor during idle periods, and it will of course be seen that the compressor will function without it inasmuch as positive opening and closing of the intake and discharge ports is accomplished by rotation of the piston 28. When the discharge port 29 passes the shoulder 51, communication between the cylinder 23 and the discharge port 26 is terminated and, as previously indicated, this point preferably corresponds approximately with the lower dead center position of the piston. Further rotation of the piston as it begins its suction stroke causes the port 29 to pass the shoulder 52 in the cylinder wall and again establish communication between the cylinder 23 and the intake chamber 25 through the intake port 24. It will be observed that the timing of the suction and discharge periods is positively controlled by the movement of the port 29 in the piston 28 past the various shoulders in the cylinder wall, and is independent of the check valve 50.

In order to insure that a body of compressed liquid is not trapped behind the check valve, the shell within which the spring of this check valve is located is preferably provided with a plurality of holes 53 as shown in Fig. 2.

It will now be apparent that a motor-compressor unit embodying the present invention is characterized by extreme compactness and the utilization of only a few moving parts which may be inexpensively manufactured. The absence of any separately operated mechanical valves eliminates the necessity of separate setting and timing operations, and materially reduces the probability of failure of the compressor to operate after being placed in service.

While the above described construction is particularly useful as a compressor for refrigerating apparatus, it may of course be utilized either as a compressor for any desired gaseous medium or as a pump for any liquid medium which it is desired to transfer from one place to another under pressure. Furthermore, merely by connecting the port 26 to a proper source of air or

other medium under pressure the mechanism may be reversely driven and caused to operate as an air motor for driving any suitable mechanism connected to the shaft 18.

5 In Fig. 9 there is shown somewhat diagrammatically an internal combustion engine of the two-stroke cycle type wherein a cylinder 55 is provided with an intake port 56 and a discharge port 57, the piston 59 which is located within the cylinder 55 being connected by a suitable connecting rod 60 to an enlarged head 61 on the engine shaft 62. The engine shaft 62 is supported in suitable bearings 63, as shown, and the enlarged head 61 on the shaft 62 is provided with a spherical socket 64 offset from the center line of the shaft 62 a distance somewhat greater than the offset distance between the center line of the shaft 62 and the center line of the piston 55, the socket 64 being adapted to receive a ball 65 on the lower end of the connecting rod 60. The intake port 56 is connected by a suitable conduit 66 to the casing 67 in which the head 61 and the rod 60 are located, and this casing is connected through a suitable flap valve 68 to a carburetor indicated diagrammatically at 69.

In this embodiment of the invention the rotary movement of the piston 59 is not utilized to control the intake and discharge ports, the operation being much the same as in heretofore known two-stroke cycle internal combustion engines, and the discharge port 57 being arranged to open a short time prior to opening of the intake port 56. Assuming that the piston 59 is at the upper end of its stroke and that ignition of the charge takes place so as to force the piston 59 downwardly, it will be observed that as the piston moves downwardly the combustible mixture contained in the casing 67 will be compressed. When the discharge port 57 is uncovered the burned gases will be discharged through the port 57, and when further downward movement of the piston 59 takes place the intake port 56 is uncovered and a fresh charge under pressure will flow from the casing 67 through the conduit 66 and the intake port 56 to the cylinder 55. Upon subsequent upward movement of the piston 59 both the intake and the discharge ports will be closed by movement of the piston and compression of the charge trapped in the cylinder 55 will thereupon occur in preparation for another firing stroke. At the same time a suction is created in the chamber 67 so as to open the flap valve 68 and draw a fresh charge from the carburetor 69. Reciprocation of the piston 59 of course causes the shaft 62 and the head 61 to be rotated by the connecting rod 60, the movement being substantially the reverse of that utilized in the compressor construction heretofore described in that reciprocatory movement is transformed into rotating movement, while in the compressor, rotation of the driving motor causes reciprocation of the compressor piston.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. In a device of the character described, the combination of a cylinder, a piston mounted in said cylinder for reciprocation and rotation

therein, a connecting rod pivoted at one end to said piston and restrained against rotation with respect to said piston, a shaft rotatable on an axis substantially parallel to but offset from the axis of said cylinder, and means pivotally connecting the opposite end of said connecting rod to said shaft for rotation therewith, the pivotal connection between said shaft and said end of said rod being radially spaced from the axis of said shaft a distance greater than the offset distance between the axis of said shaft and said cylinder whereby rotation of said shaft at a constant angular velocity causes said piston to reciprocate and simultaneously rotate through a complete revolution in said cylinder with a cyclically varying angular velocity during each reciprocation thereof.

2. In a device of the character described, the combination of a cylinder having circumferentially spaced and circumferentially extending slots in the side wall thereof forming intake and exhaust ports for said cylinder, a piston in said cylinder having a longitudinally extending slot in one side thereof for selectively connecting said intake and exhaust ports to the interior of said cylinder beyond said piston when said piston is unidirectionally rotated in said cylinder, a connecting rod pivoted at one end to said piston and restrained against rotation with respect to said piston, a shaft rotatable on an axis substantially parallel to but offset from the axis of said cylinder, and means pivotally connecting the opposite end of said connecting rod to said shaft for rotation therewith, the pivotal connection between said shaft and said rod being radially spaced from the axis of said shaft a distance greater than to the offset distance between the axes of said shaft at a substantially constant angular velocity and said cylinder whereby rotation of said shaft causes said opposite end of said connecting rod to move in a circular path offset from the axis of said cylinder simultaneously to unidirectionally rotate said piston with a cyclically varying angular velocity and reciprocate said piston.

3. In a motor compressor unit, the combination of a cup shaped supporting member having a concentric re-entrant portion in the lower wall thereof and a central aperture in said re-entrant portion, a motor having a stator positioned within said cup shaped member above said lower wall and a rotor within said stator, a shaft extending through said aperture for supporting said rotor, an enlarged circular head on said shaft within said re-entrant portion of said supporting member, a bearing ring in said re-entrant portion surrounding said circular head, a cylinder block positioned beneath said ring and said head and rigidly secured to said ring and said supporting member whereby said head is supported between said block and said supporting member and journalled in said bearing ring, said block having a cylinder formed therein extending substantially parallel to the axis of said shaft but offset therefrom, a piston in said cylinder, a connecting rod having its opposite ends respectively pivotally connected to said piston and to said head, the pivotal connection to said head being radially spaced from the axis of said shaft a distance unequal to the offset distance between the axis of said cylinder and said shaft and said rod being restrained against rotation relative to said piston whereby rotation of said head by said motor causes said piston simultaneously to reciprocate and rotate in timed relation in said cylinder.

4. The combination set forth in claim 3 wherein said cylinder is provided with circumferentially spaced slots in the side wall thereof forming intake and exhaust ports respectively, and said piston is provided with a longitudinal slot extending to the head end thereof for selectively connecting said ports to the interior of said cylinder beyond the head end of said piston as said piston is rotated and reciprocated in timed relation.

5. The combination set forth in claim 3 wherein in said enlarged circular head includes an eccentric portion, a spring pressed follower supported in said bearing ring engaging said eccentric portion to form therewith a rotary pump, means forming intake and discharge ports on opposite sides of said follower, and means respectively connecting said intake and exhaust ports with a body of oil and with said cylinder whereby pressure lubrication of said cylinder and piston is provided.

6. In a motor compressor unit, the combination of substantially cup-shaped supporting means having a concentric re-entrant portion at the bottom thereof and a central aperture in said re-entrant portion, a motor having a stator positioned within said cup-shaped means surrounding said re-entrant portion and having a rotor within said stator above said re-entrant portion, a shaft journaled for rotation extending through said aperture for supporting said rotor, radially extending means on the end of said shaft within said re-entrant portion, a cylinder block rigidly secured to said cup-shaped means positioned below said re-entrant portion and having a cylinder therein extending substantially parallel to the axis of said shaft but offset therefrom a distance less than the length of said radially extending means, a piston in said cylinder, a connecting rod having its opposite ends respectively pivotally connected to said piston and to said radially extending means, said rod being restrained against rotation relative to said piston whereby rotation of said shaft and said radially extending means by said motor causes said piston to continuously rotate in one direction in said cylinder and to reciprocate in timed relation to the rotation thereof.

7. The combination set forth in claim 6 wherein said cylinder is provided with circumferentially spaced slots in the side wall thereof forming intake and exhaust ports respectively, and said piston is provided with a longitudinal slot extending to the head end thereof for selectively connecting said ports to the interior of said cylinder beyond the head end of said piston as said piston is rotated and reciprocated in timed relation.

8. In combination, a driven element mounted for rotation about an axis and for reciprocation along the axis of rotation, a driving member mounted in spaced relation to one end of said driven member for rotation in a circular path about an axis said axis of said driving member being parallel to but laterally offset from the axis of said driven member, the offset distance being less than the radius of said circular path, a connecting rod, means connecting said rod to said driving member for universal pivotal movement and rotation with respect thereto as said driving member is rotated, and means for connecting the other end of said rod to said driven element for pivotal movement with respect thereto, said last mentioned means preventing relative rotation between said rod and said driven member whereby rotation of said driving member at a constant

angular velocity effects simultaneous rotation of said driven member continuously in one direction with a cyclically varying angular velocity and reciprocation thereof in timed relation to such rotation.

9. In a device of the character described, the combination of a cylinder, a piston mounted in said cylinder for reciprocatory and rotary movement therein, a connecting rod pivoted at one end to said piston and restrained against rotation with respect to said piston, and means for moving the opposite end of said connecting rod in a circular path at a substantially constant angular velocity about an axis of rotation, said axis of rotation being substantially parallel but offset from the axis of said cylinder to reciprocate said piston and impart thereto a rotary movement, said offset distance being unequal to and less than twice the radius of said circular path to impart to said piston a cyclically varying angular velocity which during a portion of the piston travel is greater than said constant angular velocity.

10. In a device of the character described, the combination of a cylinder, a piston mounted in said cylinder for reciprocatory and rotary movement therein, a connecting rod pivoted at one end to said piston and restrained against rotation with respect to said piston, and means for moving the opposite end of said connecting rod in a circular path at a substantially constant angular velocity about an axis of rotation, said axis of rotation being substantially parallel but offset from the axis of said cylinder to reciprocate said piston and impart thereto a rotary movement, said offset distance being unequal to and less than twice the radius of said circular path to impart to said piston a cyclically varying angular velocity which during a portion of the piston travel is greater than said constant angular velocity, said cylinder having spaced intake and discharge ports in the wall thereof, said piston having a slot therein for selectively effecting opening and cut-off of said ports, said ports and said slot being so related that cut-off of said discharge port is effected during said portion of the piston travel whereby quick cut-off and a large lap is provided.

11. In a device of the character described, the combination of a cylinder, a piston mounted in said cylinder for reciprocatory and rotary movement therein, a connecting rod pivoted at one end to said piston and restrained against rotation with respect to said piston, and means for moving the opposite end of said connecting rod in a circular path at a substantially constant angular velocity about an axis of rotation, said axis of rotation being substantially parallel but offset from the axis of said cylinder to reciprocate said piston and impart thereto a rotary movement, said offset distance being unequal to and less than the radius of said circular path to impart to said piston a unidirectional cyclically varying angular velocity which during a portion of the piston travel is greater than said constant angular velocity, said piston having a slot in one wall extending to the head end thereof, said cylinder having circumferentially spaced intake and discharge ports in the wall thereof with the cut-off edge of said discharge port and the open-

ing edge of said inlet port being so located relative to said piston slot that said slot effects cut-off of said discharge port and opening of said intake port during said greater velocity portion of said piston travel whereby quick cut-off and quick opening of said respective ports is provided.

12. In a device of the character described, the combination of a cylinder, a piston mounted in said cylinder for reciprocation and rotation therein, a connecting rod pivoted at one end to said piston and restrained against rotation with respect to said piston, and means including a rotatable shaft for moving the opposite end of said connecting rod in a circular path at a substantially constant velocity, the axis of said shaft being substantially parallel to but offset from the axis of said cylinder, the radius of said circular path being substantially greater than the offset distance simultaneously to reciprocate said piston and rotate said piston continuously in one direction in said cylinder with a cyclically varying angular velocity which during a portion of the piston travel is greater than said constant angular velocity.

13. In a device of the character described, the combination of a cylinder, a piston mounted in said cylinder for reciprocation and rotation therein, a connecting rod pivoted at one end to said piston and restrained against rotation with respect to said piston, and means including a rotatable shaft for moving the opposite end of said connecting rod at a constant angular velocity in a circular path, the axis of said shaft being substantially parallel to but offset from the axis of said cylinder, the radius of said circular path being substantially greater than the offset distance simultaneously to rotate said piston through complete revolutions in said cylinder with a cyclically varying angular velocity and to reciprocate said piston, said cylinder having in the wall thereof intake and discharge ports selectively controlled by the complete revolutions of said piston during each reciprocation thereof.

14. In a device of the character described, the combination of a cylinder having circumferentially spaced intake and discharge ports in the side wall thereof, a piston in said cylinder having a slot in one wall extending longitudinally of said piston to the head end thereof for selectively connecting said ports with the interior of said cylinder beyond the head end of said piston, a connecting rod pivoted at one end to said piston and restrained against rotation with respect to said piston, and means including a rotatable shaft for moving the opposite end of said connecting rod at a constant angular velocity in a substantially circular path, the axis of said shaft being substantially parallel to the axis of said cylinder but offset therefrom a distance substantially less than the radius of said circular path to reciprocate said piston and simultaneously rotate said piston continuously in one direction in said cylinder with a cyclically varying angular velocity which during cut-off of said discharge port is greater than said constant angular velocity whereby quick cut-off is obtained and a large lap is quickly provided to prevent leakage back through said discharge port.
